CLAIM

The ornamental design for a power cord retention device, as shown and described.

DESCRIPTION

FIG. 1 is a first perspective view of a power cord retention device;

FIG. 2 is a second perspective view thereof;

FIG. 3 is a front elevation view thereof;

FIG. 4 is a rear elevation view thereof;

FIG. 5 is a right-side view thereof;

FIG. 6 is a left-side view thereof;

FIG. 7 is a top view thereof; and,

FIG. 8 is a bottom view thereof.

The dashed lines showing portions of the power cord retention device are included for the purpose of illustrating environment and form no part of the claimed design.
